UNITED STATES PATENT OFFICE.

JOHN LALLY, OF BOSTON, MASSACHUSETTS.

CAP FOR BUILDING COLUMNS.

Application filed September 25, 1923. Serial No. 664,700.

To all whom it may concern:

Be it known that I, JOHN LALLY, a citizen of the United States, residing at Boston, in the county of Suffolk and State of 5 Massachusetts, have invented certain new and useful Improvements in Caps for Building Columns, of which the following is a specification.

My invention relates to steel caps intended 10 to replace cast iron caps on building columns and it is my object to produce a cap which will be lighter, stronger, cheaper to produce and which will not slip on the column end and which can be formed with a die in a 15 single operation. The cap is also provided with integral struts or brackets which serve to stiffen the crown plate and enable it to carry increased loads.

In the drawing Fig. 1 is a side view of 20 my improved cap, on a column, and partly in section; Fig. 2 a bottom view of the structure of Fig. 1, on the line 2—2 thereof, and partly in section; Fig. 3 is a side view of a slightly modified form of the cap on a column, partly in section; and Fig. 4 is a bottom view of the structure of Fig. 3 on the line 4—4 thereof, and partly in section.

The column proper is the usual steel tube 1 with a concrete reinforcing filling 2 therein. The cap is a steel crown plate 3 of suitable thickness to carry the desired load 30 and has the bolt holes 4, 4, 4, 4 and the flanges 5, 5, 5, 5, formed therein, preferably by the operation of a single die, the holes being punched out and the flanges slit and bent at an angle to the plate. A plurality of these flanges are formed at such distances apart that their free ends will contact with the outside of the casing 1 when the cap is 35 laid on the column thereby preventing shifting of the cap on the column. These flanges, in the preferred form of my cap, are bent at an angle of about 45° to the plane of the plate and if their ends are welded to the 40 pipe 1 they form struts or brackets supporting the crown plate 3 at some little distance from the area of contact with the end of the filled tube or pipe as well as forming a centering and retaining device which prevents 45 slipping of the crown plate or cap 3 on the pipe end.

In Figs. 3 and 4 I have shown a slight modification of the lugs 5', 5', 5', 5' which are bent at right angles to the plane of the 50 plate 3 and which contact with the exterior of the casing 1 when the cap is laid on the pipe end.

pipe end, thereby preventing shifting of the cap on the column. It is obvious that the flanges may be located inside the pipe 1 without departing from my invention.

I have found by actual use that the form of flanges shown in Figs. 1 and 2 produce the best results and that caps so made have greater load capacity than the caps of Figs. 3 and 4. Another advantage in this form of lug is that the lesser degree of bending in forming the lugs reduces the liability of breakage of the lug at the bend.

The welding may be omitted if desired and the flanges used as a centering device and 70 connection between the crown plate and pipe.

If desired that cap can be further secured to the casing or concrete, or both, in any desired manner.

A steel beam *a* or a wooden beam *b* may 75 then be laid on the cap and secured by bolts through the holes 4, 4, 4, 4.

These flanges perform the same functions as a ring around the column and hold the cap in position, the inside of the flanges 80 bearing against the outside of the casing or pipe. As the cap is preferably made of steel plate and as steel is cheaper than cast iron per pound and as the thickness of the cap is reduced one-half for the same strength 85 there is a saving of over one-half in cost from the use of my cap.

I claim:

1. A column cap comprising a plate of metal adapted to rest on a column end and 90 a plurality of flanges slit and punched from said plate at a distance from the edges thereof and bent at an angle to the plane thereof and adapted to engage the side wall of a column end.

2. A column cap comprising a plate of metal adapted to rest on a column end, a plurality of bolt holes therein and a plurality of flanges slit and punched from said plate at a distance from the edges thereof and bent at an angle to the plane thereof and adapted to engage the side walls of a column end.

3. A column cap comprising a plate of metal adapted to rest on a column end and a plurality of flanges slit and punched from said plate at a distance from the edges thereof and bent at an angle to the plane thereof and adapted to engage the side walls of a column end in combination with a column, 105 the flanges and side walls of the column being welded together.

4. A column cap comprising a plate of metal adapted to rest on a column end and a plurality of flanges slit and punched from said plate at a distance from the edges thereof and bent at an angle to the plane thereof, the free ends of said flanges being adapted to engage the side walls of a column end.
5. A column cap comprising a plate of metal adapted to rest on a column end and
10 a plurality of flanges slit and punched from

said plate at a distance from the edges thereof and bent at an angle to the plane thereof, the free ends of said flanges being adapted to engage the side walls of a column end, in combination with a column, the flange ends and side walls of the column being welded together 15

In testimony whereof I have affixed my signature.

JOHN LALLY.
